UNITED STATES PATENT OFFICE.

HENRY A. WISE WOOD, OF NEW YORK, N. Y., ASSIGNOR TO WOOD & NATHAN COMPANY, OF NEW YORK, N. Y., A CORPORATION OF NEW YORK.

SLUG-DELIVERY FOR SLUG-CASTING MACHINES.

1,075,180.

Specification of Letters Patent.

Patented Oct. 7, 1913.

Application filed September 28, 1907. Serial No. 394,955.

To all whom it may concern:

Be it known that I, HENRY A. WISE WOOD, a citizen of the United States, residing at New York, in the county of New York and 5 State of New York, have invented a new and useful Slug-Delivery for Slug-Casting Machines, of which the following is a specification.

This invention relates to the delivery of 10 cast slugs from slug casting machines.

The principal objects of the same are to provide a delivery which will operate efficiently not only with the ordinary slugs produced by line casting machines but especially 15 so that it can be used with a line casting machine when the mold of the line casting machine produces a plurality of disconnected slugs at a single operation. Also to provide a simple and efficient mechanism 20 whereby the slugs will be received and trimmed and then delivered to the galley, and to improve the various features of such a delivery mechanism.

As the invention is designed for use with 25 the ordinary line casting machines and especially for those in which the line of type is produced in a plurality of separate slugs, it will be described with particular reference to the latter construction.

Reference is to be had to the accompanying drawings in which,

Figure 1 is a front elevation of a portion of a line casting machine showing a preferred form of this invention applied thereto. Fig. 2 is a side elevation of the same. Fig. 3 is a view similar to Fig. 2 on an enlarged scale with parts removed showing certain details. Fig. 4 is a fragmentary elevation of a part of the galley. Fig. 5 is 40 a detail of certain operating connections. Fig. 6 is a view showing further details. Fig. 7 is a plan of part of the mechanism. Fig. 8 is a side elevation of the same, and Fig. 9 is a perspective view of one of the 45 ejector blades.

As this invention is illustrated with special reference to a mold capable of the producing of a plurality of slugs, certain features of such a mold will first be described.

Referring particularly to Fig. 8, it will be seen that between the liners 13 of the mold 10 there appear a number of dividing pieces 14 which divide the mold up in such a way that a plurality of separate slugs are

cast, each one having one or more letters or other characters thereon. The construction of the mold whereby this result is obtained is not described herein as it constitutes the subject of a separate invention. This mold is designed to be placed on a mold wheel or disk 15 of any ordinary or desired construction and may be manipulated in any convenient way as is well understood in this art.

This invention relates particularly to the discharge and delivery of the slugs. For this purpose an ejector mechanism is provided comprising a reciprocating member 16 having a shaft or stud 17 mounted in bearings 18 thereon. On this shaft or stud is 70 pivotally mounted a plate 19 having a bar 20 at the end thereof. A spring 21 on the member 16 operates to yieldingly hold the bar 20 in engagement with a series of ejector blades or sections 22. Each of these 75 sections will of course correspond with one of the spaces in the mold formed between the dividing pieces 14. In order that these sections may be employed when these spaces are varied, they are made removable. Each 80 one is provided with a slot 23 near the end thereof into all of which the bar 20 is adapted to engage so as to hold the several blades in registering position. The ends of the blades 22 are slanted or curved off at 85 24 so that the connection between them and the bar 20 may be made readily. Each of the ejecting blades is provided with a plurality of small longitudinal grooves 25, preferably of V-shape, on its face so that each 90 blade or section can be placed in position to enter a mold space, being guided by ridges 26 on a guide plate 27 along which the blades reciprocate.

In operation the member 16 is slid toward 95 the mold in the usual manner so that the ejector blades guided by the ridges 26, may pass into the mold or into the several mold spaces and force the slug or slugs therefrom. As the mold is ordinarily in vertical position at this time, these slugs when several are formed, are forced out to the front and between a couple of trimming knives 30 and 31, the latter of which is removable or adjustable as usual so as to provide for 105 trimming slugs of different bodies. As they pass beyond the cutting edges of the blades they will settle down into position on a rest

32, preferably on the bottom of the knife 30; thus when they are delivered, the intervening spaces made by the mold dividing pieces are closed up. As the line of slugs 5 moves forward as indicated in Fig. 7, it 10 comes between a pair of gripper jaws 33 and 34. The jaw 33 is adjusted as by placing under it shims of different thicknesses. The jaw 34 is mounted to swing on a pivot 35 mounted on the delivery gripper 36. A spring 37 yieldingly holds this gripper jaw 34 in position to engage all the slugs, it being understood that this jaw is of such length as to extend from the bottom 15 to the top of the row of slugs. The gripper jaw 34 has a projection 38 adapted to engage the end of an adjustable screw 39 mounted on a stationary part of the frame, so that when the delivery gripper 36 moves 20 up into position for gripping the slugs, the projection 38 will come into contact with the screw and move the gripper jaw 34 outwardly so as to permit the slugs to move between these jaws. Now when the delivery gripper 25 36 is moved back, the projection 38 recedes from the screw 39 and this allows the spring 37 to act immediately to bring the jaw 34 into contact with the slugs to securely hold them between itself and the jaw 33.

30 A preferred manner of operating the delivery gripper will now be described. This gripper, it will be observed, has a gripper arm 40 mounted to swing on a pivot 41 which in turn is supported by the regular linotype 35 vise 42. This vise is pivoted at the point 43 to the frame 44 of the machine and is modified in shape to fit it for carrying this gripper mechanism. It will be understood 40 that it can be swung as a whole about its pivot to make the mold gear or disk accessible from the front. The gripper arm 40 is provided with a second arm 45 operated by a link 46. This link may be operated in any desired way but is shown as having a 45 yoke 47 operated by a cam 48. This cam is preferably mounted on the regular cam shaft of the machine and developed to give an ordinary crank motion excepting that it has a slight depression 480 to provide a 50 slight dwell to hold the gripper quiet while the slugs are being forwarded into it as explained above. The swinging of the arm 40 from dotted to full line position in Fig. 2 operates the delivery gripper in the following manner: This gripper is pivotally mounted on the end of the arm 40, by means of a stud 49 and yieldingly held up by a spring 50. It is provided with a rearwardly projecting tail-piece 51 adapted to 55 engage a stud 52 fixed to the vise 42. Now when the arm 40 moves to the dotted line position after the gripper is supplied with the line of slugs, it is obvious that the gripper arm will turn about its pivot stud 49 to the position indicated in dotted lines

in Fig. 2, so as to come into registration with the galley 53. When the gripper reaches its extreme position, a cam 54 on the galley will engage a pin 55 connected with the gripping jaw 34 to turn the same 70 so as to release the line of slugs and deposit them in the galley. As the arm 40 starts to move back, the slugs left in the galley are moved forward by a spring-pressed forwarding plate 56. This is accomplished by 75 a cam 57 on the rear portion of the forwarding plate being engaged by a lug 58 on the arm 40. The cam and lug are so proportioned that the movement of the forwarding plate is equal to the width of the thickest 80 slug cast and as this movement is constant, it leaves the rear face of the slugs in the same position irrespective of their thickness. It will be obvious, of course, that as the arm 40 swings rearwardly, the gripper 85 36 will be swung upwardly by the spring 50, its motion being controlled by the cam shaped tail piece 51. When it reaches a horizontal position there will still be a slight motion of the arm 40 about its pivot. It 90 is at this point that the above mentioned dwell occurs.

From a consideration of the above, it will be seen that a delivery mechanism is provided of such form that the first motion of 95 the same is directly away from the mold and that the delivery then has a compound swinging motion about a moving pivot until it is brought into position to deposit the slugs in the galley. While on the reverse 100 motion, the compound movement is used in such a way as rapidly to swing the gripper up into position in front of the mold from which it is moved directly toward the mold about the lower pivot 41 and is allowed to 105 remain there while the slugs are being supplied to the delivery mechanism. It will be seen also that while this delivery mechanism is especially adapted by reason of the long-faced gripper jaws 33 and 34 to the 110 divided mold type of slug casting machines, yet it is also capable of general use for ordinary linotype machines. It will be seen also that the delivery mechanism described herein is especially adapted for the divided 115 mold which has been mentioned and cooperates with the special ejector mechanism in an efficient manner.

While I have illustrated and described a preferred form of the invention, I am aware 120 that many modifications may be made therein by any person skilled in the art without departing from the scope of the invention as expressed in the claims. Therefore, I do not wish to be limited to the particular form 125 shown, but

What I do claim is:—

1. In a linotype casting machine, the combination with a slug casting mold, of an ejector, a vertical trimming knife located in 130

- position to receive the slugs from the mold, and a pair of grippers for receiving the slugs from the knife, said knife having a rest at the lower edge thereof for supporting the slugs received from the mold while being gripped by the grippers. 5
2. In a linotype casting machine, the combination with a slug casting mold, of an ejector, a pair of trimming knives located in position to receive the slugs from the mold, and grippers for gripping the slugs after they pass the knives, one of said knives being laterally adjustable and the other having a rest at the lower edge thereof for supporting the slugs in position to enter the grippers. 10
3. The combination with a mold for casting slugs, of a pair of vertical trimming knives located in position to receive the slugs from the mold and trim the same as they are discharged from the mold, grippers beyond the knives, and a rest near the bottom thereof on which the slugs are supported when passing from the knives to the grippers. 15
4. In a delivery mechanism, the combination of a pair of trimming knives, a movable member, a pair of jaws located on the movable member, one of said jaws being pivotally mounted and having a stud projecting forwardly therefrom, and a stationary stop located in the path of the stud so as to engage said stud when the jaw moves toward the knives to swing said jaw away from the other jaw. 20
5. In a delivery mechanism, the combination of a stationary trimming knife, a delivery gripper movable toward and from said knife, a pair of jaws on said gripper, one of said jaws being pivoted and having a projection, a spring for forcing said pivoted jaw to closed position, and an adjustable stop mounted in stationary position adjacent to said knife for engaging said projection when the delivery gripper moves up to said knife. 25
6. In a delivery mechanism, the combination with a linotype vise, of stationary means for holding slugs to be trimmed, a stop thereon, and a movable delivery gripper supported by the vise and having a jaw movably mounted thereon, and means for engaging said stop to open the jaw. 30
7. In a delivery mechanism, the combination with a linotype vise of a swinging arm thereon, a delivery gripper movably mounted on said arm, means for controlling the motion of said delivery gripper as said arm swings, a jaw pivoted on said delivery gripper, and means for opening said jaw when the gripper moves into position to receive slugs, said means being automatically rendered inoperative when the delivery gripper recedes. 35
8. In a delivery mechanism, the combination of a linotype vise, an arm pivotally mounted thereon, means for swinging said arm, a delivery gripper pivotally mounted on said arm, and means on the vise for controlling the motion of said gripper as said arm swings. 40
9. A delivery mechanism for slug casting machines, comprising a linotype vise, a swinging arm thereon, and a delivery gripper pivotally mounted on said arm and adapted to swing about its pivot when the arm swings. 45
10. A delivery mechanism for slug casting machines comprising a linotype vise, a delivery gripper supported thereby and having swinging motions about two axes. 50
11. A delivery mechanism for slug casting machines comprising a linotype vise, a delivery gripper supported thereby and having a swinging motion about an axis, and an independent swinging motion about a second axis movable about the first axis. 55
12. In a delivery mechanism, the combination of a mold, a linotype vise, and a delivery gripper supported thereby, with means for swinging said gripper bodily toward and from the mold about an axis at a distance from the gripper and from the mold, and means for swinging the delivery gripper about a second axis which moves about the first axis and is located adjacent to the delivery gripper. 60
13. In a delivery mechanism, the combination of an arm pivoted at one end, a delivery gripper pivotally supported at the other end of said arm, said delivery gripper having a rearwardly projecting tail-piece and a stud located in position to engage said tail-piece and cause the delivery gripper to swing on its pivot when the arm swings. 65
14. In a delivery mechanism, the combination of an arm pivoted at one end, a delivery mechanism pivotally supported at the other end of said arm, and comprising a delivery gripper having a rearwardly projecting tail-piece and a stud located in position to engage said tail-piece and cause the delivery gripper to swing on its pivot when the arm swings, and means for resiliently holding said tail-piece in contact with the stud. 70
15. In a delivery mechanism, the combination of a mold, an arm adapted to move toward and from the mold, a delivery gripper pivotally mounted on said arm, and means for causing said delivery gripper to swing downwardly about its pivot when the arm recedes from the mold, and a spring for swinging the delivery gripper toward the mold. 75
16. In a delivery mechanism, the combination of a mold, a linotype vise, an arm on the vise adapted to move toward and from the mold, a delivery gripper pivotally mounted on said arm, and means for caus- 80

ing said delivery gripper to swing downwardly about its pivot when the arm recedes from the mold.

17. In a delivery mechanism, the combination of a linotype vise, a stud thereon, an arm pivotally mounted on the stud, a delivery gripper pivotally mounted on said arm, means for swinging the delivery gripper when the arm moves, and a cam for moving said arm into operative position and causing the delivery gripper to dwell in that position.

18. In a delivery mechanism for slug casting machines, the combination of a mold, an arm adapted to move toward and from the mold, a delivery gripper pivotally mounted on said arm, means for causing said delivery gripper to swing downwardly about its pivot when the arm recedes from the mold, an inclined galley below the gripper, and means connected with the galley for causing the gripper to automatically deposit slugs or type in the galley.

19. In a delivery mechanism for slug casting machines, the combination of a delivery gripper, means for moving said gripper downwardly, a jaw on said gripper, means for opening said jaw when the gripper moves into position for receiving slugs, a galley, and means on the galley for open-

ing the jaw when the gripper moves into registration with the galley, both of said jaw opening means being stationary, and a spring for closing the jaw when the gripper moves out of the way of each of said jaw opening means.

20. In a delivery mechanism for slug casting machines, the combination of a galley, a delivery gripper movable to the galley, a stationary cam on the galley, a jaw on said gripper adapted to be opened by said cam, a forwarding plate in the galley, and means for moving said forwarding plate on each stroke of the gripper.

21. In a delivery mechanism for slug casting machines, the combination of a galley, a forwarding plate therefor, a delivery gripper movable to the galley, a cam on the forwarding plate, and a lug on the delivery gripper for engaging said cam to move said forwarding plate when the gripper moves away from the galley.

In testimony whereof I have hereunto set my hand, in the presence of two subscribing witnesses.

H. A. WISE WOOD.
